UNITED STATES PATENT OFFICE.

ELMER O. BEARDSLEY, OF CHICAGO, AND WALTER F. PIPER, OF OAK PARK, ILLINOIS.

METHOD OF MAKING MOLDS FOR FOUNDRY.

1,309,835.

Specification of Letters Patent. Patented July 15, 1919.

Application filed January 29, 1919. Serial No. 273,863.

To all whom it may concern:

Be it known that we, ELMER O. BEARDSLEY and WALTER F. PIPER, both citizens of the United States, and residents of Chicago, 5 in the county of Cook and State of Illinois, and Oak Park, in the county of Cook and State of Illinois, respectively, have invented certain new and useful Improvements in Methods of Making Molds for Foundry, 10 of which the following is a full, clear, and exact description.

The invention relates to making molds for foundry.

It has heretofore been proposed to ram 15 molds by dropping sand from a high elevation or projecting the sand forcibly from a ramming head. In all of these methods which, to our knowledge, have been proposed or practised, it has been impossible 20 to rapidly produce good and satisfactory molds. In the gravity methods proposed, the desired density of the mold could not be practically attained and in machines where the sand was projected, the sand was 25 not fed with the regularity and velocity that would result in the rapid production of good molds. For these reasons, so far as we are aware, machines of this character for making sand molds for foundry have not 30 gone into general use.

The object of the present invention is to provide an improved method of making molds which will rapidly pack a mold uniformly and with great ease and facility 35 by projected wads of sand. In practice, we have discovered that by imparting an exceptionally high velocity or in excess of approximately 4,000 feet per minute, to wads of compacted sand and projecting 40 them directly into the mold, and successfully keeping the ramming head supplied with sand to uniformly produce wads, the mold will be of uniform density and quality and it becomes possible for one operator 45 and machine to make, in some instances, molds eight times as fast as can be done by hand.

The invention consists in the novel method hereinafter set forth and more particularly 50 defined by claims at the conclusion hereof.

In the drawings, which exemplify an apparatus for practising the improved method, Figure 1 is a side elevation of molding apparatus embodying the invention. Fig. 2 55 is a plan. Fig. 3 is a vertical longitudinal

section. Fig. 3^a is a section taken on line 3^a—3^a of Fig. 3. Fig. 3^b is a detail of the upper conveyer and riddle operating mechanism. Fig. 4 is a section taken on line 4—4 of Fig. 3. Fig. 5 is a plan of the 60 ramming head. Fig. 6 is a vertical axial section of the ramming head. Fig. 7 is a perspective of the rotor. Fig. 8 is a section taken on line 8—8 of Fig. 6. Fig. 9 is a section through the protective housing taken 65 on line 9—9 of Fig. 8.

The apparatus adapted for practising the improved method comprises a mast 10 which is provided at its upper end with a post 11 on which is journaled, for horizontal rotation, a tubular jib 12 which has a socket 13 around the post 11. Anti-friction bearings 13' are provided to permit free and easy lateral movement of the jib. An arm 14 is pivoted to the distal end of the jib so that 75 it and the ramming head sustained thereby can be swung horizontally, relatively to the jib. The pivotal connection between the arm and the jib consists of a hollow bracket 15 and a post 16 which is fixed to the jib 80 12 and mounted in anti-friction bearings 17 in said bracket. The body or casing 20 of an electric motor 21 is bolted, as at 22, to one side of the bracket 15, and arm 14 comprises a hollow sleeve 23 which is bolted 85 to one side of the motor casing 20 and supports the ramming head and serves also as an inclosure for the shaft 24 between the electric motor 21 and the rotor of the ramming head. This shaft is mounted in a bearing 25 in the outer end of the sleeve 23 and serves as a bearing for the outer end of 90 said shaft. The rotor for the sand for filling the flasks is fixed to the outer end of shaft 24. 95

A yoke comprising a hub 28 which is fixed and clamped, as at 27, to the sleeve 23, and arms 28' which have outwardly extending members 29 supports the casing or stator of the ramming head. This casing 100 comprises an arcuate wall 30 and an outer side wall 31.

This casing is secured to the yoke by bolt-and-slot connections 32 and set-screws 33 which are threaded to lugs 34. 105

A conveyer chute 37 containing a suitable sieve or riddle 38 is supported from the jib 12 by resilient bars 39 which have their ends respectively secured to the jib and to the chute. The inner end of chute 37 is adapt- 110

ed to receive sand from a suitable source of supply, such as a hopper 40 to which sand will be fed in any desired manner. The outer end of chute 37 discharges into the 5 upper open end of an inclined chute 35 which is fixedly mounted on the arm 14, and is supported by bars 36 so that the relation between the arm, chute 35 and the ramming head remains fixed. The upper end 10 of the chute 35 and the outer end of the chute 37 are disposed adjacent the axis about which the arm 14 swings, so that the relative movement of the chutes will maintain the discharge into the chute 35. The chute 15 37 and the riddle therein are vibrated by a pitman 41 which is pivoted to chute 37 and is operatively connected to an eccentric or wrist-pin 42 on a shaft 43 which is journaled in a bracket fixed to the upper end of the 20 socket 13. An electric motor 44 is also mounted on said bracket and a pinion on the shaft of said motor meshes with a gear 46 which operates the shaft 43 and eccentric 42. This mechanism serves to shake the 25 chute 37 and the riddle to cause it to disintegrate the sand and to discharge it regularly and continuously into the upper end of the chute 35 which is inclined sufficiently to cause the sand to flow lengthwise thereof 30 and be discharged into the ramming head continuously by gravity. This construction exemplifies mechanism for feeding sand to the ramming head in which the chute on the outer arm is rigid therewith, so that no 35 shaking mechanism for said chute is necessary.

The chute 35, as more clearly seen in Figs. 6 and 8, discharges into the open side 40 of the ramming head. The centrifugal force has a tendency to stick the sand into the ramming head instead of spattering it outwardly by centrifugal force, as occurs when the sand is delivered to the periphery of the rotor. The rotor is adapted to receive the sand at the open side of the head 45 and to project it downwardly into the mold. The rotor comprises a hub 50 and a cylindrical body 51, integral with the hub and secured to shaft 24, an inclined guide-flange 50 52 which is flared inwardly from the periphery of the inner side of the cylindrical body 51 and directs the sand onto the body 51. The guide-flange 52 is formed as a ring 55 and is bolted to said body, as at 53. A curved outwardly extending bed 54 integral with the rotor-body, is adapted to support the projector blade 55. Said blade is curved to fit the bed 54 and is provided with an inner side wall 56 which has a curved edge 57 and 60 is adapted to function as a positive cut-off for the sand, so that as the rotor is revolving, the wall 56 will shear a portion of the sand issuing from the lower end of the chute from the sand in the chute. The rotor 65 is counterweighted, as at 58, to balance the

projector blade and its bed 54 and cause the rotor to run evenly at a very high speed. When the rotor is operated at a high speed, its curved base and centrifugal force cause the wad of sand which has been separated 70 from the supply in the chute 35 to wedge and impact itself in the corner between the outer end of the plate and arcuate wall 30 of the casing, as shown in Fig. 8, so that before the wad reaches the point of discharge, at 75 60, it will have been densified and packed into a proper mass for projection into the mold. This construction of ramming head is peculiarly adapted for high speed operation, such as has been found necessary to 80 form good molds.

A protective housing 61, which is out of contact with the rotor, is suspended from the extensions 29 of the supporting yoke. It is desirable to have the head as open as 85 possible to avoid atmospheric resistance to the high speed rotor and to have as short and rapid an operative stroke of the rammer blade as possible, since otherwise excessive power would be necessary to operate the 90 rotor. For this purpose, the inner side of the stator is open and the wall 30 of the stator or casing begins at a point which is reached by the projector-blade shortly before it reaches the incoming sand stream 95 from chute 35 and terminates at 60, where the wad will be discharged truly downward into the mold. The wall 64 of the protective housing is disposed in off-set relation with respect to the discharge point 60. A 100 three-sided wear-plate 65 is secured in the housing. A handle 71 is secured to the ramming head, whereby the operator can easily move the head laterally to distribute the projected sand to all portions of the mold. 105

In the practice of the improved method, the mold-material or sand is delivered into the chute above the jib and thence into the feed-chute 35 so that the sand will be delivered into the side of the stator or to one 110 side of the rotor in a substantially continuous stream, the rotor blade serving to shear off predetermined or regular quantities and forming them into wads. The motor 67 is driven at approximately 1140 115 revolutions per minute and usually has, when making molds for gray-iron, a radial distance between the axis of the rotor and the arcuate wall of the stator of about seven inches. In making such molds, the sand 120 may be fed to the rotor at the rate of seven cubic feet per minute. The wads of sand will be projected into the mold at the rate of approximately 4000 feet per minute and in rapid succession, corresponding to the number of revolutions per minute of the motor and rotor. This high speed of rotation will cause the wads to be compacted in transit through the ramming head by centrifugal 125 force and the action of the blade before they 130

are projected into the flask. The operator, grasping the handle 71, will move the head over the mold to distribute the wads and evenly form all portions of the mold. The sand is projected in a constant vertical direction and as a result the previously deposited wads are not materially disturbed by the incoming wads and, therefore, the mold material is evenly densified in the mold.

10 In making molds for steel castings, apparatus is used which is adapted to impart movement to the wads of sand in the ramming head at a speed ranging from 7000 to 8000 feet per minute; the rotor is operated at a speed ranging approximately from 15 1600 to 1800 revolutions per minute and the sand is supplied to the head at the rate of approximately ten cubic feet per minute. When the wads of sand are projected into 20 the flask at this high rate of speed, the molds will be adapted for steel castings.

The present method makes it possible to fill flasks and make molds very rapidly and economically.

25 The improved method, by reason of the high speed of projection and delivery of wads of mold-material, has been found, in practice, to produce molds which are superior to, and more regular than, molds 30 formed by hand, besides producing them with greater rapidity and at a lower cost for labor.

Another characteristic of the improved method is the uniform quality of the molds 35 resulting from the high speed projection of the sand, and this lessens spoilage of castings due to defective filling of the molds.

A characteristic of the present method is that the sand is delivered into one side of the 40 ramming head and the rotor shears a sufficient quantity to form a wad from the stream moving laterally into the head and this is conductive to supplying the sand to the rotor in sufficient volume to cause the wads 45 to be rapidly and regularly projected into the flasks.

The invention is not to be understood as restricted to the precise details of practice set forth, since these may be modified without departing from the spirit and scope of 50 the invention.

Having thus described the invention, what we claim as new and desire to secure by Letters Patent, is:

55 1. That improvement in making molds which consists in projecting wads of mold material into a flask at a velocity of not less

than approximately 4000 feet per minute to form a mold.

2. That improvement in making molds 60 which consists in projecting compacted wads of mold-material into a flask at a velocity of approximately not less than 4000 feet per minute to form a mold.

3. That improvement in making molds 65 which consists in shearing wads transversely from a stream of mold-material to form wads and projecting them at a high velocity into a flask to form a mold.

4. That improvement in making molds 70 which consists in shearing wads transversely from a stream of mold-material to form wads by centrifugal force, compacting the wads, and projecting them at a high velocity into a flask to form a mold. 75

5. That improvement in making molds which consists in shearing wads of mold-material from a substantially continuous stream of mold material, and projecting the wads at a high velocity and in rapid succession 80 into a flask to form a mold.

6. That improvement in making molds which consists in feeding mold-material in a substantially continuous stream to a ramming head at the rate of approximately 85 seven cubic feet or over per minute and projecting wads of sand at a high velocity and in rapid succession into a flask to form a mold.

7. That improvement in making molds 90 which consists in feeding mold-material in a stream to a ramming head at the rate of approximately seven cubic feet or over per minute and rotating the wads at a high velocity of approximately 4000 feet or over 95 per minute and projecting the wads of the mold-material into a flask to form a mold.

8. That improvement in making molds which consists in delivering mold material 100 to one side of a rotary projector in a direction transverse to the plane of its rotation, shearing regular quantities from the material and projecting the wads at high velocity into a flask.

9. That improvement in making molds 105 which consists in delivering mold material to a rotary projector and discharging wads of mold material into a mold at high velocity and moving the projector laterally to distribute the wads throughout the mold and 110 maintaining a constant angle of delivery.

ELMER O. BEARDSLEY.
WALTER F. PIPER.
